MICROWAVE OVEN

Hiroshi Kikuchi, Ikeda, and Akiyoshi Koshiro, Yoshiaki Kawata, and Masami Ueda, Nara, Japan, assignors to Matsushita Electric Industrial Co., Ltd., Osaka, Japan

Filed June 6, 1973, Ser. No. 367,403

Claims priority, application Japan Dec. 13, 1972

Term of patent 14 years

Int. Cl. D7—02

U.S. Cl. D7—128

FIG. 1

FIG. 2

FIG. 3

FIG. 1 is a front perspective view of a microwave oven showing our new design,

FIG. 2 is a rear perspective view thereof, and

FIG. 3 is a front perspective view of a second embodiment thereof, the only difference residing in the appearance of the front panel.

We claim:

The ornamental design for a microwave oven, as shown and described.
